DESIGN FOR A DOLL LAMP

Caroline M. Terrell and Louis Binder,
New York, N. Y.

Application March 6, 1935, Serial No. 55,749

Term of patent 3½ years

To all whom it may concern:

Be it known that we, Caroline M. Terrell and Louis Binder, citizens of the United States and residents of New York, in the county of New York and State of New York, have invented a new, original, and ornamental Design for a Doll Lamp, of which the following is a specification, reference being made to accompanying drawing, forming part thereof.

Figure 1 is a view showing a front elevation of the lamp showing our new design.

Figure 2 is a view showing a side elevation of the lamp.

The lamp consists of two dolls standing with their backs against the lamp post, with a lamp at the top of the post above the heads of the dolls and a shade on the lamp. A loop forming a handle also extends upward from the post at a point between the dolls' heads and extends over the lamp and shade.

We claim:

The ornamental design for a doll lamp, substantially as shown and described.

CAROLINE M. TERRELL.
LOUIS BINDER.
